UNITED STATES PATENT OFFICE.

FRANK W. LEWIS, OF DAVENPORT, IOWA, ASSIGNOR TO THE BETTENDORF COMPANY,
OF BETTENDORF, IOWA, A CORPORATION OF IOWA.

SIDE FRAME FOR CAR TRUCKS.

Application filed March 7, 1928. Serial No. 259,678.

This invention relates to side frames for car trucks and has for its object to provide a one-piece side frame in which the tension and compression members are so constructed 5 and so joined at the ends of the frame that the compression and tension stresses are substantially balanced in the end portions of the frame directly over the journal boxes and so distributed that the load is imposed 10 on the journal boxes centrally thereof without crowning or otherwise destroying the journal boxes.

Other objects are to provide a side frame casting of such form that it may be made in 15 a mold having simple and easily positioned cores and, in addition, to provide a casting of such form that in the casting operation, the molten metal flows readily to all portions of the casting, so that the danger of developing 20 flaws in making the casting are substantially eliminated.

A further object is to provide a cast side frame having a compression member so joined to the tension member and the journal 25 boxes that the compression and tension stresses are substantially balanced in the end portions of the frame centrally over the journal boxes.

With the above and other objects in view, 30 the invention may be said to comprise the structure as illustrated in the accompanying drawings hereinafter described and particularly set forth in the appended claims, together with such variations and modifications 35 thereof as will be apparent to one skilled in the art to which the invention appertains.

Reference should be had to the accompanying drawings forming a part of this 40 specification in which:

Fig. 1 is a fragmentary view showing 45 an end portion of a truck frame embodying the invention in longitudinal section, the section being taken on the line indicated at 1-1 in Fig. 2.

Fig. 2 is a fragmentary top plan view showing one end of the side frame.

Fig. 3 is a section taken on the line indicated at 3-3 in Fig. 1.

Fig. 4 is a section taken on the line indicated at 4-4 in Fig. 1.

In the accompanying drawings, one-half only of the side frame is shown, since the opposite ends are identical, as well understood in the art.

The side frame of the present invention is a one-piece casting of truss form having a compression member 1, which may be straight, and a tension member 2, which merge into an extension 3 at each end of the frame, to which a journal box 4 is integrally united. A tension member 2 has a horizontal central portion 5, which forms a support for one end of the spring plank upon which the bolster supporting springs are seated. 60 The central portion 5 of the tension member is connected at each end with an end portion 3 of the frame, through an upwardly inclined portion 6 at each end thereof. The tension member is connected with the compression member 1 by an integral column 7 adjacent each end of the central portion 5, the column 7 being integral with the lower inner ends of the inclined portions 6 of the tension members, and forming the opposite 75 sides of a central opening in the side frame, which receives the truck bolster.

The compression member, as shown in Fig. 3, is of channel form in cross section, having a web 8 on the upper side thereof and vertical side flanges 9 depending from the web, the lower edges of the flanges being provided with a thickened or beaded edge portion 10, which serves to increase the rigidity and strength of the compression member. 85

The tension member 2 is also of channel form in cross section and may have its channel facing either upwardly or downwardly. As shown herein, the tension member has 90 on its under side a web 11 and vertical side flanges 12 extend upwardly from the web 11, the cross sectional form of the tension member being substantially the same as that of the compression member. The side 95 flanges 9 and 12 of the compression and tension members merge into side walls 13 of the end portion 3 of the frame, which are relatively deep as compared to flanges 9 and 12. The side walls 13 at the ends of the frame are integrally united with the journal boxes 4 across the top of the journal box and part way down the inner side of the journal box; the web 11 of the tension chord extending to the side wall of the journal box and being integrally united therewith. 100

The end portions 3 of the side frame are rounded over the top of the journal box and terminate adjacent the outer side of the journal box. The upper portions of the side 110

walls 13 being joined by an integral web 14, which is separated from the web 8 of the tension member by tapering opening 15, which bifurcates the inner end of the web 14 and provides at the end thereof tapering ribs 16 which merge into the side walls adjacent the end of the compression member.

The web 8 of the compression member has at each end, a downwardly inclined extension 17, which extends beneath the opening 15 and web 14 to a point spaced above the journal box and located substantially over the center of the journal box. The extension 17 has a bifurcated end portion formed by a tapered recess 18 so that the end of the extension terminates in tapering ribs 19, which merge into the side walls.

The web 14 is preferably provided with an opening 20 between its outer end and 20 the upper edge of the journal box, this opening being also of a form such that the web has tapering end portions 21 merging into the side walls 13, at the top of the journal box.

25 The openings 15 and 20 and the space between the lower end of the extension 17 and the top of the journal box permit the core sand to be readily removed from the casting and also greatly simplify the construction 30 and assembly of the mold cores. It will thus be seen that the reinforcing web 17 extends downwardly over the journal box and terminates substantially at its intersection with the projected neutral axis of the tension 35 member at a point centrally over the journal box. The bifurcated ends of the web 14 of the compression chord and of the reinforcing web 17 providing the tapering ribs merging into the side walls serve to evenly 40 distribute the stresses at the end of the frame and to protect the journal box from stresses which would otherwise create distortion 45 therein. In addition, the end of the frame is so formed that the metal will readily flow up to any portion of the casting in a mold built 50 to form the casting, so that danger of creating flaws or cracks in the casting are substantially eliminated.

Furthermore, it is to be understood that 55 the particular form of apparatus shown and described, and the particular procedure set forth, are presented for purposes of explanation and illustration and that various modifications of said apparatus and procedure can be made without departing from my invention, as defined in the appended claims.

What I claim is:

1. A truck frame having journal boxes at 60 the ends thereof, top and bottom compression and tension members cast in one piece, end portions integral with the compression and tension members and extending across the tops of the journal boxes, said members being of channel form and said end portions 65 having side walls into which the flanges of

the compression and tension members merge, and a reinforcing web extending across the space between the side walls of each end portion, said reinforcing webs extending downwardly from the web of the compression 70 member at an inclination thereto and having their ends terminating over said journal boxes and carried by the side walls of the compression member.

2. A truck frame having journal boxes at 75 the ends thereof, top and bottom compression and tension members cast in one piece, end portions integral with the compression and tension members and extending across the tops of the journal boxes, said members being of channel form and said end portions having side walls into which the flanges of the compression and tension members merge, a reinforcing web extending across the space between the side walls of each end portion, said reinforcing webs extending downwardly from the web of the compression member at an inclination thereto 80 and terminating over said journal boxes at a point substantially central with respect to the journal box and substantially in the projected neutral axes of the tension member, and a web connecting the upper edges of the side walls of each end portion and overlying the reinforcing web.

3. A truck frame having journal boxes at 85 the ends thereof, top and bottom compression and tension members cast in one piece, end portions integral with the compression and tension members and extending across the tops of the journal boxes, said members being of channel form and said end portions having side walls into which the flanges of the compression and tension members merge, a reinforcing web extending 90 across the space between the side walls of each end portion, said reinforcing webs extending downwardly from the web of the compression member at an inclination thereto and terminating substantially over the axes of said journal boxes, the end of each reinforcing web being spaced from the top of the journal box, and webs connecting the upper edges of the side walls of the end 95 portions and overlying the reinforcing webs, each web having bifurcated end portions forming openings, adjacent the outer edges of the journal boxes and over the inner ends of said reinforcing webs.

4. A one-piece cast truck frame having 100 journal boxes at the ends thereof, a compression member of channel form having downwardly extending flanges, a tension member of channel form, an end portion having side walls into which the flanges of 105 said members merge, said side walls being integrally united with the journal box across the top and at the inner side thereof, and a reinforcing web forming a continuation of the web of the compression member and 110

formed integrally with the side walls, said reinforcing web extending downwardly between said side walls at an inclination to said web of the compression member to a point substantially over the center of the journal box.

5. A one-piece cast truck frame having journal boxes at the ends thereof, a compression member of channel form having downwardly extending flanges, a tension member of channel form, an end portion having side walls into which the flanges of said members merge, said side walls being integrally united with the journal box across the top and at the inner side thereof, a reinforcing web forming a continuation of the web of the compression member and formed integrally with the side walls, said reinforcing web extending downwardly between said side walls at an inclination to said web of the compression member to a point substantially over the center of the journal box, and a web joining the top portions of said side walls above said reinforcing web, the ends of said web being bifurcated to provide end portions merging into the side wall adjacent said reinforcing web and adjacent the outer edge of the journal box and to provide openings to the interior of the casting over the journal box.
- 10
- 15
- 20
- 25
6. A one-piece cast truck frame having

journal boxes at the ends thereof, a compression member of channel form having downwardly extending flanges, a tension member of channel form, an end portion 30 having side walls into which the flanges of said members merge, said side walls being integrally united with the journal box across the top and at the inner side thereof, a reinforcing web forming a continuation of the 35 web of the compression member and formed integrally with the side walls, said reinforcing web extending downwardly between said side walls at an inclination to said web of the compression member to a point substantially over the center of the journal box, and a web joining the top portions of said side walls above said reinforcing web, the ends of said web being bifurcated to provide end portions merging into the side wall 40 adjacent said reinforcing web and adjacent the outer edge of the journal box and to provide openings to the interior of the casting over the journal box.

45

In testimony whereof I affix my signature.

FRANK W. LEWIS.
